TOY BELLS

Richard Gratzer, Liverpool, England

Application November 12, 1954, Serial No. 468,485

Claims priority, application Great Britain
November 13, 1953

1 Claim. (Cl. 46—174)

This invention relates to ornamental bells of the type which are customarily made of thin glass and used on festive occasions for decorative purposes, or as toys; and aims to simplify the construction of such bells and so cheapen the cost of manufacture. Said bells are usually formed with a tapered re-entrant lower portion, at the apex whereof there is sealed by hand into a provided aperture a metallic loop whereto the upper end of a wire is connected; and to the free end of said wire a member—usually a bead—constituting the bell's clapper is secured.

The present invention provides a bell of attractive appearance adapted for machine manufacture and which obviates necessity for the hand-sealing in position of the before referred-to metallic loop.

In carrying out my invention, I manufacture a hollow bell body of thin glass, or other suitable material—such as a substance now commonly known and referred to as a "plastic"—which is of conventional bell shape or configuration, but the lower end whereof is completely closed.

A clapper bead, or its equivalent, is attached to an end of a thin wire, cord, or the like, which depends within the hollow bell body and its upper end is associated with a cap piece fitted on an integral neck formed for its reception on the top of said bell body.

Preferably, a wire loop piece—having outwardly biased spring arms which are entered through an opening in the cap and, by, frictional contact with the inner surface of said neck, holds said cap in position—provides a means whereby the bell may be suspended on a Christmas tree or elsewhere; and, conveniently, the upper end of the clapper-carrying wire may be attached to the wire loop on the inside of the cap. Thus, the clapper is secured against upward displacement from its most effective sounding position.

To enhance the pleasing appearance of the bell, a bulbous projection may be formed in the centre of the closure of its lower end.

I will further describe my invention with the aid of the accompanying drawings which illustrate, by way of example only and not of limitation, one mode of embodiment.

2

In said drawings:

Fig. 1 is a sectional elevation, and

Fig. 2 is a perspective view of a toy bell.

Fig. 3 is a fragmentary view, drawn to an enlarged scale as compared with the preceding views, showing the upper part of the bell and its cap prior to assembly.

Referring now to said drawings, *a* denotes a bell-shaped hollow body of thin glass, or other suitable substance, having an open upper neck portion *b* and a closed convex lower part *c* in the centre whereof has been formed a bulbous projection *d*. A cap *e*, which may be of metal, is fitted to neck portion *b* and is apertured as at *f* to receive the divergent arms *g* of a coil spring *h*.

As shown most clearly in Fig. 1, said cap *e* is held in position by the frictional engagement of arms *g* against the annular shoulder *a'* of the hollow body *a* under the influence of the coil spring *h* which is arranged to bias apart its integral arms *g*. The clapper of the bell is constituted by a bead or bob *i* attached to the lower end of a length of wire *j* the upper end whereof passes through the aperture *f* of cap *e* and is conveniently secured to a convolution of said coil spring *h*.

The outer surface of the bell thus formed may be coloured and ornamented in any desired manner, the whole presenting a pleasing and attractive appearance eminently suited to the end in view.

Coil spring *h*, in addition to providing a strong and reliable mode of attachment of cap *e* to the bell body, also functions as a means whereby the bell may be suspended in required position.

I find in experimental practice that the sounding of a bell constructed according to my invention is louder and has a more pleasing tone than the tinkling of similarly sized bells of conventional construction.

What I claim as my invention and desire to secure by Letters Patent is:

An ornamental bell comprising a hollow closed bottom bell-shaped body provided with an annular shoulder and an open neck extending outwardly from said shoulder, an apertured cap mounted on and enclosing said body neck, a coil spring having integral biased-apart spring arms extending through the aperture of said cap and into said body neck frictionally engaging said annular shoulder tending to retain said cap on said body neck, a clapper, and a member carrying said clapper swingably connected to said coil spring and extending through the aperture of said cap and said body neck depending with said clapper within said bell shaped body.
